Primary Examiner — Kimberly Barnes(74) *Attorney, Agent, or Firm* — Reed Smith LLP; Walter M. Egbert, III; Richard J. Brown(57) **CLAIM**

The ornamental design for a helmet, as shown and described.

DESCRIPTION

FIG. 1 is a top left front isometric view of a helmet showing our new design;

FIG. 2 is a top left rear isometric view thereof;

FIG. 3 is a bottom right rear isometric view thereof;

FIG. 4 is a front view thereof;

FIG. 5 is a rear view thereof;

FIG. 6 is a right view thereof;

FIG. 7 is a left view thereof;

FIG. 8 is a top view thereof; and,

FIG. 9 is a bottom view thereof.

The broken lines in FIGS. 1-9 depict portions of the helmet that form no part of the claimed design.

1 Claim, 9 Drawing Sheets
